**COMBINED ESCUTCHEON AND FACE PLATE
FOR A TELEVISION RECEIVER CABINET**

John W. Mason, Glenview, Ill.

Application August 9, 1957, Serial No. 47,289

Term of patent 3½ years

(Cl. D56—4)

Fig. 1 is a front perspective view of a combined escutcheon and face plate for a television receiver cabinet, showing my new design;

Fig. 2 is a fragmentary sectional view on line 2—2 of Fig. 1;

Fig. 3 is a fragmentary sectional view on line 3—3 of Fig. 1; and

Fig. 4 is also a fragmentary sectional view on line 4—4 of Fig. 1.

The dominant features of my new design reside in the portion thereof shown by full lines in the drawing.

I claim:

The ornamental design for a combined escutcheon and face plate for a television receiver cabinet, as shown and described.
